UNITED STATES PATENT OFFICE

105,784

DESIGN FOR A TEXTILE FABRIC OR SIMILAR ARTICLE

Arnold Zavell, New York, N. Y.

Application July 26, 1937, Serial No. 70,645

Term of patent 3½ years

To all whom it may concern:

Be it known that I, Arnold Zavell, a citizen of the United States, residing in the city of New York, county of New York, and State of New York, have invented a new, original, and ornamental Design for a Textile Fabric or Similar Article, of which the following is a specification, reference being had to the accompanying drawing, forming a part thereof.

The figure is a plan view of a textile fabric showing my new design.

The design consists of a series of entwining strips of crinkled material superimposed upon a substantially smooth background giving it a raised appearance.

I claim:

The ornamental design for a textile fabric or similar article as shown and described.

ARNOLD ZAVELL.
